(57) **CLAIM**

The ornamental design for an eyewear hinge assembly, as shown and described.

DESCRIPTION

FIG. 1 is a perspective view of the new design;

FIG. 2 is a top view thereof;

FIG. 3 is a bottom view thereof;

FIG. 4 is a front elevation view thereof;

FIG. 5 is a rear elevation view thereof;

FIG. 6 is a right side elevation view thereof, the left side being a mirror image of the right side;

FIG. 7 is a right side elevation view thereof; and,

FIG. 8 is a right side elevation view of the eyewear hinge assembly in an alternate configuration of use.

The broken lines showing an eyewear frame and lenses depict environmental subject matter and form no part of the claimed design.
